ANTIRACING VALVE FOR STEAM-DRIVEN
FEED PUMPSErich W. Henkel, Calumet City, Ill., assignor to
Combustion Engineering-Superheater, Inc.,
New York, N. Y.

Application November 4, 1949, Serial No. 125,401

3 Claims. (Cl. 103—16)

1

The present invention relates to pumps and particularly to an improved means for preventing racing of a steam driven feed pump when it loses suction.

Steam driven feed water pumps are liable to race or run away in the event that the water side of the pump becomes air bound or the water supply fails due to emptying of the supply tank or disruption of piping connecting the latter to the pump. The invention contemplates the provision of a control valve in the exhaust line from the steam cylinder of a reciprocating feed water pump which is subject to water delivery pressure so that it moves towards closed position on loss of pump suction and builds up a high exhaust pressure that acts to prevent racing of the pump. The invention is also applicable to centrifugal pumps.

In the drawings;

Figure 1 is a diagrammatic view of a pump system embodying the present invention; and

Figure 2 is a sectional view on an enlarged scale of the control valve embodied in the system of Figure 1.

In Figure 1 there is represented a conventional reciprocating feed water pump having one or more steam cylinders 10 receiving steam through the piping 11 and discharging exhaust steam through the pipe 12. Water is drawn into the water cylinders 13 of the pump from the supply tank 14 through a pipe 15 and is forced through the pipe 16 to a boiler or other point of use.

In accordance with the present invention there is interposed in the exhaust steam line 12 a control valve designated as a whole by the numeral 20 in Fig. 1. The exhaust steam enters the valve casing 20 through the pipe 12 and passing through the valve chamber 23 is discharged through a pipe 21. This flow is subjected to control of the valve member 24 in chamber 23 which in Figure 2 is illustrated as being seated. This valve member 24 has a by-pass port 25 connecting its inlet and outlet sides so that even when the valve 24 is in closed position a small amount of steam may pass to the vent pipe 22. The stem 30 of valve 24 is connected to a pressure responsive diaphragm or bellows 31 located in a chamber 32 that is connected by a pipe 33 with the feed line 16 leading from the delivery side of the pump. Thus, the bellows 31 is subjected to the water delivery pressure which acts thereon in a direction to open the valve 24 against the resistance of a spring 34 located within the bellows. A by-pass line 36 connecting with the feed line 16 leads back to the water supply tank 14 and has a re-

striction 37 therein. This by-pass is provided to safe-guard the operation of the control apparatus against a leaky boiler check valve as at 38. The by-pass also serves the useful purpose of eliminating from the water system any air that may have accumulated when the pump is started after a prolonged period of shut down.

Assuming that the pump is applied to a boiler which carries a normal operating steam pressure of 250 p. s. i. and that the steam flow to the pump through pipe 11 is regulated automatically by a water regulator which is set to maintain a constant water level in the boiler drum. During normal operation the anti-racing valve 20, 24 in the pump exhaust line will be held in wide open position by the pump delivery pressure acting on bellows 31. Inasmuch as the valve member 24 in its open position offers very little resistance to the flow of exhaust steam, the exhaust steam pressure at the pump will be low or "normal." Should a water supply failure at the water end of the pump occur, which in turn will cause the pump delivery pressure to drop below e. g. 60 p. s. i. for which the spring inside the bellows is set, the spring 34 will force the valve 24 to its closed position. The steam leaving the pump must then pass through port hole 25 which will induce a considerable restriction to the steam flow. It follows that the exhaust pressure between valve 20 and pump cylinder 10 becomes abnormally high. The pump steam side becomes "steam locked," forcing the pump to run at an idling speed as long as there is steam entering the pump until conditions at the pump water end are corrected whereupon a water delivery pressure of above 60 lbs. is sufficient to open the valve 24 again. The high exhaust pressure at the pump is immediately released and the pump again is prepared to operate at "normal."

What I claim is:

1. In combination with a steam operated pump drawing water from a source of supply and introducing it into a feed line provided with a check valve, and an exhaust pipe connected to the steam side of the pump; a control valve in said pipe; means responsive to a predetermined pressure of water delivered by said pump for opening said valve; spring means associated with said valve for moving it to closed position when the water delivery pressure falls below said predetermined value; and a by-pass associated with said exhaust line and valve for permitting escape of steam to enable continued operation of said

pump when said delivery pressure falls below said value.

2. In combination with a steam operated pump drawing water from a source of supply and introducing it into a feed line provided with a check valve, and an exhaust pipe connected to the steam side of the pump; a control valve in said pipe; means responsive to a predetermined pressure of water delivered by said pump for opening said valve; and means operative when said water pressure falls below a predetermined value to act upon said valve so as to restrict the flow of exhaust steam in said pipe and thereby preclude racing of said pump.

3. In combination with a steam operated pump drawing water from a source of supply and introducing it into a feed line provided with a check valve, and an exhaust pipe connected to the steam side of the pump; a control valve in said pipe; pressure responsive means connected to said valve arranged when subjected to a predetermined pressure to move said valve in a

direction to open it; a pipe connecting said feed line to said pressure responsive means for subjecting said means to the delivery pressure of said pump to cause opening of said valve when said pressure reaches a predetermined value; means acting to close said valve; a water return between said feed line and said supply source; and restrictive means in said return line for limiting the flow therethrough.
